Primary Examiner—Louis S. Zarfas*Assistant Examiner*—Greg Andoll*Attorney, Agent, or Firm*—Marshall A. Lerner; Bradford E. Mattes; Kleinberg & Lerner, LLP[57] **CLAIM**

The ornamental design for a shoe upper, as shown and described.

DESCRIPTION

FIG. 1 is a perspective view of the front, left and top of a shoe upper showing my new design.

FIG. 2 is a left side elevational view thereof;

FIG. 3 is a top plan view thereof;

FIG. 4 is a right side elevational view thereof;

FIG. 5 is a front elevational view thereof; and,

FIG. 6 is a rear elevational view thereof.

The broken line showing of the sole in the figures is for illustrative purposes only and forms no part of the claimed design.
